UNITED STATES PATENT OFFICE.

ROSE SAHLIN, OF CHICAGO, ILLINOIS.

DESIGN FOR A WAIST-FRONT DISTENDER.

SPECIFICATION forming part of Design No. 28,536, dated May 3, 1898.

Application filed October 28, 1897. Serial No. 656,713. Term of patent 3½ years.

To all whom it may concern:

Be it known that I, ROSE SAHLIN, a citizen of the United States, residing at Chicago, county of Cook, and State of Illinois, have invented and produced a new and original Design for a Waist-Front Distender, which is fully set forth in the following specification, reference being had to the accompanying drawings, forming a part thereof.

This invention is a design for an article of ladies' wear of the class of garment-distenders; and specifically it is a design for a device to distend or maintain a puffed or inflated appearance in the waist portion of an outer garment above the belt or waistband-line at the front.

In the drawings, Figure 1 is a perspective view of a waist-distender of my design. Fig. 2 is an outline of the same at the plane of the line 2 2 on Fig. 1.

This design is characterized by the single unitary swell A, which is symmetrical about a medial vertical fore-and-aft plane through the crest or foremost point of the swell and which viewed in respect to vertical curvature slopes off somewhat gradually to the armpit-line a, which is the upper limit of the device,

and more abruptly downward to the waistband b. The shape of this swell A is further characterized by the curvature in horizontal plane, which diminishes from a plane through the point of greatest vertical expansion (indicated by the line 2 2) almost to flatness at the plane of the line a, the horizontal curvature below the plane of the line 2 2 being such as to cause the lines of vertical curvature to merge in a curve which is an approximate circle at the waist.

The drawings represent the necessary shoulder, waist, and bust straps for securing the device in position on the form; but these are not characteristics of the design.

I claim—

The design for a waist-front distender herein shown and described.

In testimony whereof I have hereunto set my hand, in the presence of two witnesses, at Chicago, Illinois, this 25th day of October, 1897.

ROSE SAHLIN.

Witnesses:

M. SAHLIN,
CHAS. S. BURTON.
